UNITED STATES PATENT OFFICE.

CHARLES C. SCHUTTE, OF INDIANAPOLIS, INDIANA.

AUTOMATIC CONTROLLING DEVICE FOR PRINTING MACHINES.

Application filed August 15, 1925. Serial No. 50,505.

My said invention relates to automatic controlling devices for printing machines and it is an object thereof to provide interdependent controlling means for air and gas supplies such as are used in printing presses of certain types.

The general character of the machine to which my present improvements are or may be applied is disclosed in my Patent No. 1,429,301, September 19, 1922. As is well known to those skilled in the art difficulty arises in the handling of newly printed sheets in the press such difficulty being due in large part to the static electricity with which the machines become charged. To overcome this it is customary to heat the sheets by means of a gas flame as they leave the periphery of the impression roller and are discharged on the guide fingers from which they are taken by rocking fly sticks and deposited in a pile on the receiving table of the press.

Another difficulty that is commonly experienced consists in the tendency of the corners and edges of the newly deposited sheets to curl up as the fly sticks recede, whereupon they are liable to be creased at the corners by the sheet next following. Air pipes are provided by means of which jets of air are projected on the parts of the sheets thus liable to be rolled up, such jets holding these parts of the sheets down and preventing them from being bent down and creased by the sheets subsequently added to the pile. It is also customary to force the jets of air in between the descending sheet and the remainder of the pile both to retard its descent and for drying the ink thereon to prevent smudging of the sheets.

In the practice of my invention I have provided interconnected means for supplying air and gas for the purposes indicated together with a common automatic control for such means.

Referring to the accompanying drawings which are made a part hereof and on which similar reference characters indicate similar parts:

Figure 1 is an elevation of the mechanism above referred to,

Figure 2, a longitudinal section of the automatic controlling devices,

Figure 3, a transverse section on line III-III of Figure 2,

Figure 4, a transverse section on line IV-IV of Figure 2, and

Figure 5, a horizontal section on line V-V of Figure 2.

In the drawings reference character 1 indicates an air inlet pipe communicating in turn with the cut-out 2, a pipe 3, flexible tubing 4 and pipes 5-5, the latter leading into an automatic controlling device at 6 and the air passing through a body member 20 to emerge at 7 where it enters a distributing pipe 8. Said air distributing pipe has perforations 9 arranged in any conventional or desirable manner along one or more sides thereof. A gas pipe 10 enters the automatic control at 11 and the gas passes through a body member 21 forming the lower part of said control and out by way of a port 12 which communicates with a pipe 13 having perforations 14, these perforations providing jets from which the gas emerges to form the flame for heating the printed sheets. In effect the body members are pipe sections of somewhat irregular form to permit them to be joined together as hereinafter described.

A pipe 15 projects from one side of the automatic control and is provided adjacent its outer end with an aperture 16 for a pilot flame. The cut-out 2 is closed by a lever 17 when the press is stopped as by a cylinder trip or other device and at this time the compressed air in the automatic control and parts leading thereto is exhausted into the atmosphere by means of pipe 18. A spring 19 closes the cut-out when the pressure on lever 17 is relieved.

The automatic control comprises two body members 20 and 21 which are provided with a common wall 29 here shown as forming a part of the section 21. They are also provided with flanges 22 and 23 having flat meeting faces to permit an air-tight engagement, said flanges being held together by screws 24. The body member 21 has a partition 27 extending across the same and this partition has a port which may be closed by a valve 30 having a tapered seating portion 32 fitting in a seat 31. The valve 30 is provided with guiding flanges 33 and a stem 34. A spring 35 extends downward from the head of the valve and rests at its lower end in a seat formed by a hollow screw 45. The screw 45 has engagement with a hollow screw 44 which is internally threaded throughout its length. A lock-nut 46 is threaded on the screw 44 and a locking screw 47 has threaded engagement with an open-

105
head of the valve and rests at its lower end in a seat formed by a hollow screw 45. The screw 45 has engagement with a hollow screw 44 which is internally threaded throughout its length. A lock-nut 46 is threaded on the screw 44 and a locking screw 47 has threaded engagement with an open-

2
ing in the head of screw 45. The locking screw 47 is provided with a lock-nut 48. It will be seen that the locking means locks the two hollow screws in place and that a considerable range of adjustment is provided for the spring 35 so as to vary its action on the valve.

The stem 34 of the valve projects up through an aperture in the partition 29 between the two body members, said partition in this instance being formed integral with the lower body member. A valve member 36 pivoted at 37 on lugs 38 has a bend or bight resting on the upper end of said valve stem. It will be seen that the valve 36 projects into the path of the air current through the body member 20. So long as there is a considerable air current passing the valve 36 it will force the valve 30 downward so as to open the port through the partition 27 and permit gas to flow to the pipe 13, but when the air current fails the spring 35 can lift the valve 30 and close the port, forcing the valve 36 toward upright position. It will be evident that the air current will cease when the lever 17 is operated against the tension of the spring 19 and that thereupon the flow of gas will also cease. The pilot light, however, continues to burn as it is supplied through a port 49 in the lower body member which port leads to the aperture at 16 from a point back of the partition 27.

A passage is also provided at 40 through the partition 29 by means of which air is supplied to the current of gas and this passage may be regulated by means of a screw 41 having a tapered end portion so as to provide the correct amount of air for commingling with the gas to produce the most efficient combustion. A lock-nut 42 is mounted on the screw 41 for securing it in place.

It will be obvious to those skilled in the art that various changes may be made in my device without departing from the spirit of the invention and therefore I do not limit myself to what is shown in the drawings and described in the specification, but only as indicated in the appended claims. It will also be obvious that the device may be used for other analogous purposes and in other machines than printing presses, as a device of this character may be useful wherever the flow of one fluid is to be controlled by the presence or absence of a different current of fluid or fluent material in another location, which location may be immediately adjacent to the first as in the present illustration or may be at a distance therefrom.

Having thus fully described my said invention, what I claim as new and desire to secure by Letters Patent, is:—

1. In a printing press having feeding means for sheets of paper and pneumatic controlling means for such sheets, a pipe having a plurality of outlets for emission of

air under pressure, a gas pipe having a plurality of outlets adjacent the path of the sheets of paper, means for stopping the flow of air to the air emission pipe, and means controlled by the flow of air for stopping and starting the flow of gas in the gas pipe, substantially as set forth. 70

2. In a printing press having feeding means for sheets of paper and pneumatic controlling means for such sheets, a pipe having a plurality of outlets for emission of air under pressure, a gas pipe having a plurality of outlets adjacent the path of the sheets of paper, means for stopping the flow of air to the air emission pipe, means controlled by the flow of air for stopping and starting the flow of gas in the gas pipe, 75 80 85 said means comprising a valve in the gas pipe, a valve in the air pipe, and resilient means tending to close the valve, substantially as set forth.

3. In a printing press having feeding means for sheets of paper and pneumatic controlling means for such sheets, a pipe having a plurality of outlets for emission of air under pressure, a gas pipe having a plurality of outlets adjacent the path of the sheets of paper, means for stopping the flow of air to the air emission pipe, means controlled by the flow of air for stopping and starting the flow of gas in the gas pipe, 90 95 a pilot light adjacent said gas pipe, and a passage to said pilot light from a point anterior to said valve, substantially as set forth. 100

4. In a printing press having feeding means for sheets of paper and pneumatic controlling means for such sheets, a pipe having a plurality of outlets for emission of air under pressure, a gas pipe having a plurality of outlets adjacent the path of the sheets of paper, means for stopping the flow of air to the air emission pipe, means controlled by the flow of air for stopping and starting the flow of gas in the gas pipe, 105 110 115 and a passage from the air pipe to the gas pipe at a point in the gas pipe anterior to said outlets, substantially as set forth.

5. In a printing press having feeding means for sheets of paper and pneumatic controlling means for such sheets, parallel air and gas pipes having spaced outlets at intervals in their length, parallel pipe sections connected to said pipes, a partition in one of said sections said partition having a port, a valve for the port, a pivoted valve in the other pipe section operable by the current in said pipe to open said first-named valve, and constantly-acting means tending 120 125 to close said valve, substantially as set forth.

6. In a printing press having feeding means for sheets of paper and pneumatic controlling means therefor, parallel air and gas pipes having spaced outlets at intervals 130

in their length, parallel pipe sections connected to said pipes, a partition in one of said sections said partition having a port, said valve having a stem extending into the other section, means in said other pipe section operable by the current therein to control said valve through its stem, a spring pressing said valve toward its seat, and means operable from the outside of the 10 valved pipe section for adjusting the tension of said spring, substantially as set forth.

7. The combination of a pair of fluid con-

duits, a valve in one of said conduits, a spring for closing said valve, and a valve 15 in the other conduit connected to the first-named valve for opening it against the pressure of the spring under the influence of a current in the second conduit, substantially as set forth. 20

In witness whereof, I have hereunto set my hand and seal at Indianapolis, Indiana, this 13th day of August, A. D. nineteen hundred and twenty-five.

CHARLES C. SCHUTTE. [L. S.]
